(57) **CLAIM**

The ornamental design for a rack-mounted enclosure, as shown and described.

DESCRIPTION

FIG. 1 shows a right side perspective view of a rack-mounted enclosure according to an embodiment of this invention, the bottom surface is flat and the undisclosed left side is a mirror image of the right side.

FIG. 2 shows a front view of the design according to an embodiment of the invention.

FIG. 3 shows an enlarged view of the region inside the dash-dot-dash bracket in FIG. 2.

FIG. 4 shows a sectional view taken along line 4—4 in FIG. 3.

FIG. 5 shows a top view of the design according to an embodiment of the present invention; and,

FIG. 6 shows a rear view of the design according to an embodiment of the invention.
